UNITED STATES PATENT OFFICE.

SIGMUND HERBERT, OF NEW YORK, N. Y.

DESIGN FOR A GLASS DISH.

40,807.

Specification for Design.

Patented Aug. 2, 1910.

Application filed June 2, 1910. Serial No. 564,714. Term of patent 3½ years.

To all whom it may concern:

Be it known that I, SIGMUND HERBERT, a citizen of the United States, and a resident of the city of New York, county of New York, and State of New York, whose post-office address is 48 West Broadway, in said city, have invented a new, original, and ornamental Design for a Glass Dish, of which the following is a specification.

Reference is to be had to the accompanying drawing forming a part hereof, illustrating in perspective a glass dish embodying my design.

I claim:—

The ornamental design for a glass dish as shown herein.

SIGMUND HERBERT.
